[57] CLAIM

The ornamental design for combined instant camera
and printer, as shown and described.

DESCRIPTION

FIG. 1 is a top, front and left side perspective view of a
combined camera and printer showing our new design
thereof;

FIG. 2 is a top, rear and right side perspective view
thereof;

FIG. 3 is a bottom, front and right side perspective view
thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a left side elevational view;

FIG. 9 is a right side elevational view; and,

FIG. 10 is a top, rear perspective view of the camera
processing the exposed printing paper.

The broken lines representing the printing paper in
FIG. 10, is shown for illustrative purposes only.
